UNITED STATES PATENT OFFICE.

NANNIE R. MITCHELL, OF PARIS, KENTUCKY.

DESIGN FOR A PURSE.

SPECIFICATION forming part of Design No. 33,980, dated January 29, 1901.

Application filed November 24, 1900. Serial No. 37,680. Term of patent 7 years.

To all whom it may concern:

Be it known that I, NANNIE R. MITCHELL, a citizen of the United States, residing at Paris, in the county of Bourbon and State of Kentucky, have invented and produced a new and useful Design for a Purse, of which the following is a specification, reference being had to the accompanying drawing, forming part thereof, the same illustrating my design in ⁵ elevation.

As shown in the drawing, the leading or material feature of my design consists of an essentially rectangular-shaped central portion A, having a semicircular-shaped flap B. At ¹⁵ the opposite side edges of the main or body portion A are side members or portions D and H, having their edges tapering toward their outer ends, where they merge into the side edges of elongated portions C and G, which

are considerably narrower in width than the ²⁰ width of the body portion. Elongated portion C is considerably longer than portion G, and its outer end is rounded, as shown at E, and formed therein adjacent to said rounded end is a series of circular openings F. Elongated portion G carries at its outer end an essentially semicircular bail I, crossed by a bar K.

Having thus fully described my invention, what I claim as new, and desire to secure by ³⁰ Letters Patent of the United States, is—

The design for a purse substantially as herein shown and described.

NANNIE R. MITCHELL.
